UNITED STATES PATENT OFFICE.

JAMES T. HOGAN, OF JERSEY CITY, NEW JERSEY, ASSIGNOR TO THE NATIONAL MACHINE COMPANY, OF NEW YORK.

STOP-MOTION FOR SEWING-MACHINES.

SPECIFICATION forming part of Letters Patent No. 644,801, dated March 6, 1900.

Original application filed February 20, 1899, Serial No. 708,801. Divided and this application filed June 30, 1899. Serial No. 722,398. (No model.)

To all whom it may concern:

Be it known that I, JAMES T. HOGAN, a citizen of the United States of America, residing in Jersey City, county of Hudson, and State 5 of New Jersey, have invented a certain new and useful Improvement in Stop-Motions for Sewing-Machines, of which the following is a specification.

My invention relates to a stop-motion comprising a brake and belt-shipping mechanism more particularly designed for use on sewing-machines, the present application being a division of an application, Serial No. 708,801, filed by me February 20, 1899.

15 I will describe my improvement, and then point out the novel features in claims.

In the accompanying drawings, in which similar letters of reference indicate similar parts, Figure 1 is a side elevation of my improvement applied to a buttonhole-machine, only sufficient of the latter being shown as is necessary to illustrate the invention. Fig. 2 is an end elevation of the same, and Fig. 3 is an inverted plan of a slide-rod and toggle device comprised in the improvement.

A designates the bed-plate, and A' the head, of a sewing-machine of any suitable form.

B designates the main driving-shaft, rotatably mounted in the head of the machine in 30 the well-known manner. B' is a loose pulley, and B² a fast pulley, on said shaft.

B³ is the driving-belt. Forming part of the pulley B² or otherwise rigidly secured to the main driving-shaft is a disk or plate C, having on its face a projecting piece C', made, preferably, with a beveled or cam surface, as shown. This piece C' is so placed on the disk C that it will contact with a suitable friction-brake so as to stop the rotation of the main 40 driving-shaft at or about the time when the needle is at its highest point, thus relieving the operator of the necessity of turning the shaft to release the work.

D designates a rod located below the bed-plate of the machine and supported so as to slide freely in suitable brackets a a' a², secured to or forming a part of said plate. To 45 the end D' of said rod are attached levers E and E' by means of screw-studs e² and e³.

The said levers are respectively fulcrumed on 50 studs e⁴ and e⁵, secured to a bracket A², fastened by suitable means, as screws or bolts a⁴, to the head or base of the machine. The ends e and e' of levers E and E', respectively, are slotted, as shown, to permit the adjustment of said levers on the end D' of rod D. The bolt of screw-stud e² is set eccentrically 55 on the body to permit of the adjustment of lever E to compensate for the wear of the face of brake-shoe F, such form of stud being well known. To the upper end of lever E, I secure a brake-shoe F, having preferably a flat face f, of leather or other suitable material. To the upper end of lever E', I secure an arm E², having a fork E³ to engage 60 the belt B³.

The parts above described are normally held in the position shown in the drawings by means of a spring G, supported on the rod D between the bracket a and an adjustable 70 collar g on said rod—that is, the spring G tends to move the rod D inward or to the left, and thus holds the brake-shoe F in contact with the projection C' of the disk C and the belt B³ on the loose pulley B'.

H designates a toggle mechanism, the arm h of which is pivoted on a stud h² of a collar D², rigidly secured by a screw d to the rod D. The other arm h' is pivoted on a stud h³ of a bracket H³, secured by a bolt h⁴ to the bracket 80 a³. To the hook H', secured to the ends of the stud H³, which unites the inner ends of arms h and h', is attached a strap or cord under the control of the operator. A screw J passes through the arm h' and bears against 85 the rod D, and by adjusting said screw the throw of the toggle may be varied.

The operation of my improvement is as follows: In starting the machine the operator pulls on the strap attached to the hook H' and holds or secures the same. This opens the toggle-levers, moves the rod D, outward and thus releases the brake-shoe F from contact with the surface of the projection C', and ships the belt B³ from the loose to the fast 95 pulley. When the operator has completed his work, the treadle-strap is released. This permits the spring G to move the rod D to

the left, thus shipping the belt to the loose pulley B' and bringing the shoe F into such position that rotation of the main driving-shaft is stopped when said shoe frictionally 5 engages the projection C'. By beveling the faces of the projection C' the stoppage of the shaft B is effected gradually and no strain is put upon the parts of the mechanism, although a flat face is within my invention.

10 The toggle mechanism H plays an important function in this connection, as after it is closed in the position shown it aids the spring G to prevent the movement of the rod D outwardly and holds the lever E with its shoe F positively in position. To draw the toggle-levers h and h' up quite horizontal, I attach a spring K to the bed-plate and to one of the said levers, as h', so that with the levers in such position the pressure on the brake-shoe F will

15 20 not rock them open.

What I claim, and desire to secure by Letters Patent, is—

- 25 1. In a sewing-machine the combination of a rod movably supported in suitable brackets, a lever provided with a brake-shoe and actuated by said rod, a main driving-shaft, a cam-surface on said shaft, a spring to normally hold the brake-shoe in contact with said cam, and a toggle-lever connected to said rod, substantially as described.
- 30 2. In a sewing-machine the combination of a rod movably supported in suitable brackets,

ets, a lever provided with a brake-shoe and actuated by said rod, a main driving-shaft, a cam-surface on said shaft, a spring to normally hold the brake-shoe in contact with said cam, a toggle-lever connected to said rod, and means to limit the throw of said toggle-lever, substantially as described.

35 40 3. In a sewing-machine the combination of a main driving-shaft having fast and loose pulleys, and also a cam-surface thereon, a rod and means to actuate the same, a brake-lever adapted to engage said surface, and a belt-shipping lever, both of said levers connected to and actuated simultaneously by said rod, substantially as described.

45 4. In a sewing-machine the combination of a main driving-shaft having fast and loose pulleys and also a cam-surface thereon, a rod 50 movably supported in suitable brackets, a brake-lever and a belt-shipping lever both of which are secured to said rod, a spring to normally hold the brake-lever in engagement with said cam-surface and the belt on the 55 loose pulley, and a toggle-lever connected to said rod, substantially as described.

In testimony whereof I have signed my name to this specification in the presence of two subscribing witnesses.

JAMES T. HOGAN.
